POGO STICK

Herman I. Rapaport, Chicago, Ill.

Application May 9, 1957, Serial No. 658,093

3 Claims. (Cl. 272—57)

This invention relates to improvements in Pogo sticks.

One of the objects of the invention is to provide a Pogo stick which has a leg member of supporting pole which is retractable when not in use to reduce the length of the unit to permit shipment and storage of same in a minimum of space.

Another object of this invention is to provide a Pogo stick with a retractable supporting pole which is retractable within the frame of the unit so that the overall length of the unit is substantially the length of the frame. This permits mailing of the unit in containers of a length to conform to post office requirements and also enables the unit to be placed in containers or cartons of considerably less size than if the unit were not thus retracted.

Another object is to provide a Pogo stick in which the spring element is completely enclosed thereby eliminating the hazards of soiling the clothes by the lubricant used in connection with the spring and also eliminating the hazard of catching the clothing or parts of the body in the compressible coils of the spring. The appearance of the unit is also enhanced thereby.

Other objects will become apparent as this description progresses.

In the drawings:

Figure 1 is an elevational view, partially in cross section showing my Pogo stick in extended position ready for use.

Figure 2 is a view of the Pogo stick in collapsed or retracted position as for shipping.

Figure 3 is a view partially in cross section taken on line 3—3 of Figure 1.

Figure 4 is a view taken on lines 4—4 of Figure 1.

Figure 5 is a view taken on lines 5—5 of Figure 1.

Figure 6 is an enlarged cross sectional view taken on lines 6—6 of Figure 3, and

Figure 7 is an enlarged cross sectional view taken on lines 7—7 of Figure 2.

The Pogo stick has a platform for the feet which platform is generally indicated at 10 and which is formed of two plates or two sections 12 joined together. The plates 12 are of identical construction and the same numbers will be applied thereto. Each plate is formed with a semi-circular central portion 14 so that a central circular opening 16 is provided when the plates 12 are joined together. The upper portions of each of the plates adjacent their opposite ends are turned outwardly to provide half disc shaped plates 18 with a downwardly extending flange 20, so that a circular disc shaped foot rest 22 is provided when the two sections are joined together. Each of the plates 12 is formed to provide angular ribs 24 for strengthening the plates. The two plates 12 are permanently secured together by a plurality of rivets 26 and spotwelds. A rubber foot pad 28 is secured to each of the foot rests 22 and said foot pad has a downwardly extending rim 29 and inwardly directed flange 30 as best seen in Figure 3, which permits the foot pad to be detachably secured to the foot rest 22.

Secured to the platform 10 are a pair of uprights or vertically positioned tubular members 32 of identical con-

2

struction. The lower ends of each of the tubular members 32 is slotted as at 34 (Figure 7) to fit over the platform 10 and is permanently secured thereto by rivets 36. The uprights 32 are spaced from each other throughout their length except that they are inclined inwardly at the top as at 28 for abutting relation and there secured together by a permanent rivet pin 40. The tubular members turn outwardly to form handles 42 and the handles are provided with rubber gripping members 44. A pair of cross bars 46 are permanently secured by four rivet pins 47 to the tubular members 32 and the cross bars 46 are each formed to provide a central semi-circular shaped portion 48 which bars together form a central circular opening 49 for passage of a leg or supporting pole 50.

The leg or supporting pole generally indicated at 50 is formed of a tubular member and is supported at its upper end within the opening 49 of the cross bars 46 and is supported at its lower end within the circular opening 16 of the platform 10. Supported on the tubular leg or supporting pole 50 adjacent the cross bars 46 is an inverted cup shaped member on collar 52 which has an enlarged central opening 54 in the top thereof for passage of the tubular pole 50 as best seen in Figure 3. A coil spring 56 surrounds the supporting pole 50 and the upper end 25 of the spring is supported within the inverted cup shaped member or collar 52. Supported on the supporting pole adjacent the platform 10 is a cup shaped member or collar 58 best seen in Figure 6, having a bottom 59 which has an enlarged central opening 60 for passage of the pole 50. The lower end of the spring 56 is confined or supported in the cup shaped member or collar 58 which is detachably secured to the supporting pole as will be described. The collar 58 extends downwardly of the horizontal bottom 59 of the member and said downwardly extending 30 portion is provided with a pair of aligned oppositely positioned slots 64 opening downwardly. The supporting pole 50 has a pair of aligned transverse openings 66 which receive a threaded fastener 68. The opposite ends of the threaded fastener 68 being received in the slots 64 of the collar 58 to retain the collar 58 and prevent it from moving downwardly on the supporting pole 50. The pole is provided with a rubber tip 51 at the bottom thereof.

As best seen in Figures 1 and 3, the spring 56 bears against the collar 58 but the collar is prevented from moving downwardly by virtue of the threaded fastener 68. The collar thus forms a base support for the spring 56. Figures 1 and 3 show the position of the supporting pole and the parts when the Pogo stick is in position for use or play.

50 The upper end of the supporting pole 50 has a plurality of spaced pairs of aligned transverse openings 70 for receiving a threaded fastener 72 which will rest against the top of the cross bars 46 to compress the spring 56. As shown in Figures 1 and 3, the spring 56 is held in a compressed position on the supporting pole 50 between the two cup shaped members or collars 52 and 58 and the frame of the stick. The frame generally being formed by the uprights 32 and platform 10. The frame is supported on the pole 50 under tension and elevated to its uppermost position in relation to the supporting pole 50. By standing on the feet support of the platform, the child's weight will move the frame downwardly on the supporting pole 50 and compress spring 56 as the pole 50 rests on the ground or a floor surface.

65 When the pole 50 is lifted from the ground or floor surface as is done in play as is well understood in the art, the frame will move upwardly with respect to the pole 50 due to the spring 56 until the pole 50 again strikes the ground or floor surface and the frame again moves downwardly with respect to the supporting pole. This permits the child 70 to hop about on the Pogo stick. Normally the threaded fastener 72 is not used, however to increase the compres-

sion of the spring 56, the threaded fastener 72 is inserted in any of the transverse openings 70 on the supporting pole 50.

For best use the spring 56 is lubricated by a grease or oil with some of the grease or oil retained in the cup shaped members 52 and 58. The grease will normally tend to spatter when the Pogo stick is used. As the spring 56 compresses and decompresses, there is also present the danger of getting the child's clothing or a part of the body caught in the spring. To overcome these objections, there is provided a sleeve generally indicated at 76 which surrounds the spring 56 and whose opposite ends are secured inside the upper and lower cup shaped members 52 and 58. The sleeve 76 is made of a Vinylite plastic material which is flexible so that as the upper cup shaped member 52 moves downwardly with the frame in relation to the lower fixed cup member 58 the sleeve will flex along its length and will again assume its normal full length position when the upper cup shaped member 52 is in its uppermost elevated position.

The overall length of the Pogo stick when in its play position is as shown in Figure 1, and is of such length that problems are presented in packaging and shipment of same. Enlarged cartons would be required adding costs and space and also making it impossible to ship through the mails. With this invention the foregoing objections are eliminated as the supporting pole 50 may be moved inwardly or retracted inside the frame, reducing the overall length of the unit for shipment to substantially the length of the frame. This is best shown in Figure 2. To accomplish this, the threaded fastener 68 is withdrawn from pole 50 thus releasing the lower collar 58 from its engagement with the pole and the pole 50 is pushed upwardly or inwardly inside the frame as shown in Figure 2.

During shipment the removed threaded fastener 68 may be temporarily inserted in any of the openings 74. Also to reduce the size of the carton, the rubber foot pads 28 may be removed from the foot members 22 and placed in the carton. The unit is ready for use after removal from the carton by moving the pole 50 downwardly and inserting the threaded fastener 68 as shown in Figure 1.

In place of the threaded fasteners 68 and 72 cotter pins may be used.

It will be understood that various changes and modifications may be made from the foregoing without departing from the spirit and scope of the appended claims.

I claim:

1. A Pogo stick comprising a foot rest, a pair of uprights secured to said foot rest, said uprights supporting a handle at the upper ends thereof, an upper cross member secured to said uprights below said handle and defining an unobstructed space between said uprights and above said upper cross member and below said handle, an inverted cup shaped member positioned against said upper cross member, a supporting pole extending between said uprights and through said inverted cup shaped member, a lower cup shaped member surrounding said pole, a pin detachably secured to said pole, and engaged by said lower cup shaped member to limit the downward movement of said lower cup shaped member, a coil spring surrounding said pole with the opposite ends of the spring positioned in said aforementioned cup shaped members, said pin when detached from said pole adapted to release said lower cup shaped member from securing to said pole to permit retraction of said pole upwardly between said uprights so that the upper portion of said supporting pole extends into said unobstructed space above said upper cross member and below said handle and the lower ex-

tremity of the pole is positioned adjacent the foot rest so that substantially the entire pole in said retracted position is located within the length of said uprights and said foot rest.

5. 2. A Pogo stick comprising a foot rest, a pair of uprights secured to said foot rest, said uprights supporting a handle at the upper ends thereof, an upper cross member secured to said uprights below said handle and defining an unobstructed space between said uprights and above 10 said upper cross member and below said handle, an inverted cup shaped member positioned against said upper cross member, a supporting pole extending between said uprights and through said inverted cup shaped member, a lower cup shaped member surrounding said pole, a pin 15 detachably secured to said pole and engaged by said lower cup shaped member to limit the downward movement of said lower cup shaped member, a coil spring surrounding said pole with the opposite ends of the spring positioned in said aforementioned cup shaped members, said pin when detached from said pole adapted to release said lower cup shaped member from securing to said pole to permit retraction of said pole upwardly between said uprights so that the upper portion of said supporting pole extends into said unobstructed space above said upper cross member and below said handle and the lower extremity of the pole is positioned adjacent the foot rest so that substantially the entire pole in said retracted position is located within the length of said uprights and said foot rest, and a sleeve surrounding and enclosing said spring 25 with the opposite ends of the sleeve retained within said cup shaped members.

3. A Pogo stick comprising a platform formed of two plates joined together to form a central guide opening and a pair of spaced circular foot rests at the opposite ends thereof, a resilient circular foot pad detachably secured to each said circular foot rest, a pair of uprights secured at their lower ends to said platform, said uprights each having a laterally extending handle at the upper end thereof, an upper cross member secured to said uprights 10 below said handle members and defining an unobstructed space between said uprights and above said cross member and below said handles, an inverted cup shaped member positioned against said upper cross member, a supporting pole extending between said uprights and through said upper cross member and said inverted cup shaped member and said central guide opening, a lower cup shaped member surrounding said pole, a pin detachably secured to said pole and engaged by said lower cup shaped member to limit the downward movement of said lower cup shaped member, a coil spring surrounding said pole with the opposite ends of the spring positioned in said aforementioned cup shaped members, said pin when detached from said pole adapted to release said lower cup shaped member from securing to said pole to permit retraction of said pole upwardly between said uprights so that the upper portion of said pole extends into said unobstructed space above said upper cross member and below said handles and the lower extremity of the pole is positioned adjacent the platform so that substantially the entire pole in said retracted position is located within the length of said uprights and said platform, and a sleeve surrounding and enclosing said spring with the opposite ends of the sleeve retained within said cup shaped members.
